UNITED STATES PATENT OFFICE.

SALVATORE MASTROIANNI, OF WATERBURY, CONNECTICUT.

PERIODICAL-CALL APPARATUS.

1,223,286.

Specification of Letters Patent. Patented Apr. 17, 1917.

Application filed November 13, 1914. Serial No. 872,002.

To all whom it may concern:

Be it known that I, SALVATORE MASTROIANNI, a subject of the King of Italy, residing at Waterbury, county of New Haven, 5 State of Connecticut, have invented an Improvement in Periodical-Call Apparatus, of which the following description, in connection with the accompanying drawing, is a specification, like characters on the drawing 10 representing like parts.

This invention relates to periodic call apparatus designed to give a signal or alarm at predetermined time intervals, and it has for its object to provide a novel apparatus 15 of this nature which is provided with means for adjusting the time interval so that the call can be given at the end of time intervals of any desired length and also to provide a device which can be used equally well for 20 giving a signal after a predetermined number of revolutions or movements in a machine or part with which it is associated. Another object is to provide a construction of this nature by which the call may be a 25 short or a long call as desired. Further objects of the invention are to provide a novel construction which can be readily attached to an ordinary alarm clock movement thereby converting it into a periodic call apparatus, and further to improve devices of this 30 nature, all as will be more fully hereinafter described and then pointed out in the appended claims.

Referring now to the drawings wherein 35 I have illustrated a selected embodiment of my invention, Figure 1 is a view of an alarm clock movement equipped with my periodic call apparatus;

Fig. 2 is an enlarged fragmentary view 40 showing parts of the call apparatus in the position which they assume when the call is being given;

Fig. 3 is a side view of Fig. 2;

Fig. 4 is a view of an alarm clock embodying my invention;

Fig. 5 is a view similar to Fig. 2 showing 45 a different form of the invention;

Fig. 6 is a fragmentary view showing the

manner of locking the call apparatus from 50 operation.

Fig. 7 is a sectional view on the line $x-x$ Fig. 1.

My invention is of such a nature that it can be used in connection with a uniformly-moving member, as, for instance, some part 55 of a clock train, for giving a call or alarm at the end of predetermined time intervals, or in connection with any rotating part to give a call or alarm after said part has made a predetermined number of rotations. A 60 simple embodiment of the invention is one wherein it is used in connection with a clock train for giving the alarm at the end of predetermined time intervals, and a device of this nature has, therefore, been illustrated in 65 the drawings.

I have shown at 1 a clock frame having the usual clock train designated generally by 2 by which the center arbor 3 carrying the minute hand is operated, and as usual 70 in clock mechanism the hour hand is mounted on a sleeve carried by the center arbor and driven from reducing gearing from the arbor 3, two members of this reducing gearing being shown at 4 and 5, respectively. 75 The clock herein shown is of the alarm clock variety, the alarm of which is caused by a vibrating member 6 actuated by a toothed wheel 7 rotating on the usual shaft 8, said toothed wheel 7 being actuated from a 80 spring 9 by a train of gearing 10, as usual in alarm clocks. The construction as thus far described is of the type ordinarily found in alarm clocks and forms no part of the present invention.

In applying my invention to an alarm clock I provide means normally locking the alarm mechanism from rotation and also provide a releasing member which is normally geared to the clock train so as to 90 rotate therewith, said releasing member being constructed to release the lock for the alarm mechanism after a predetermined time interval. I also provide means for disconnecting the releasing member from its driving member when the alarm is sounded, and 95

for restoring the releasing member to neutral position for the commencement of another time interval. The device also comprises an adjustable stop member which 5 limits the restoring movement of the releasing member and which can be adjusted so that the releasing member will be actuated at the end of a time interval of any predetermined length.

10 For normally locking the alarm mechanism from operation I have provided the shaft 8 with a member 11 fast thereon carrying a finger 12 which normally engages a stop projection 13. This projection 13 is 15 adapted to be moved out of engagement with the finger 12 by a releasing member which is driven from some part of the clock movement and, therefore, has a regular uniform rate of speed. This releasing member 20 is herein shown as a disk or gear 14 which is geared to a gear 15 fast with the gear 5, although the releasing member might be driven from any one of the gears of the clock train without departing from 25 the invention. The releasing member is acted upon by a return spring which is wound up as said releasing member moves forwardly and means are provided for disconnecting the releasing member from the 30 gear 15 when the alarm is sounded, at which time the return spring automatically returns the releasing member to its zero position so that it starts its forward movement again. This releasing member 14 is herein 35 shown as rotatably mounted on a carrier 16 which is pivotally mounted at 17 on the clock frame, and it has projecting therefrom a releasing pin 18 which is active in releasing the stop 13 from the finger 12. In the 40 embodiment shown in Fig. 1 the stop 13 is carried by an arm 19 that is pivotally mounted at 20 to the carrier 16, and said stop 13 extends through an opening 21 in the carrier 16 and through an opening in 45 the frame 1 into position to coöperate with the projection 12. The free end of the arm 19 is in the path of movement of the releasing pin 18 so that as the releasing member 14 rotates the releasing pin 18 engages the 50 arm 19 and swings it up about its pivot 20 sufficiently to release it from the finger 12. When this occurs, the alarm mechanism is released and the signal will be given.

55 As stated above I have provided means whereby at the time that the signal is given the releasing member 14 will be disconnected from the gear 15 and will be returned to its zero position by a return spring. This return spring is shown at 22 60 and is received in a recess 23 formed in the frame of the releasing member 14, one end of the spring being connected to the releasing member, as at 24, and the other end of the spring being connected to a shaft 25

that extends axially through the releasing member. The means for disconnecting the releasing member from the gear 15 is herein shown as a cam 26 rigid with the member 11 and situated to engage the projection 13 as the shaft 8 rotates. Whenever the stop 70 member 13 is raised by the releasing member, as above described, and the alarm mechanism is thereby released, the cam member 26 will be turned into the dotted line position Fig. 2 thereby engaging the stop 13, 75 raising the latter in the aperture 21 until it strikes the periphery of the aperture, and thereafter the action of the cam against the member 13 will raise the carrier 16 about its pivot 17 into the position shown in Fig. 80 2 thereby disengaging the releasing member 14 from the gear 15. As soon as the releasing member is disengaged from the gear 15, the spring 22 will return the releasing member to its normal or zero position, 85 and this return movement will occur before the cam 26 has passed out from under the stop member 13. As soon as the cam does pass out from under said projection the carrier 16 will be returned to its normal 90 position by means of the spring 27, thus bringing the releasing member 14 into engagement with the gear 15 again and upon the continued rotation of the shaft 8 the finger 12 will come around into engagement with the stop member 13 thereby bringing the parts to rest. The alarm will, 95 therefore, be sounded while the shaft 8 makes one complete revolution.

100 The zero position of the releasing member is determined by a positioning member herein shown as a disk 29 carrying a positioning pin 30 that is adapted to be engaged by a projection extending from the releasing member. In the present embodiment 105 of my invention I extend the releasing pin 18 through the releasing member a sufficient distance so that the projecting end thereof will constitute this projection. The positioning member 29 is adjustable about its axis so as to bring the positioning pin 30 110 into any desired position, dependent on the desired length of the time intervals. This time interval is the time taken for the releasing pin 18 to travel from the positioning pin 30 up into a position to engage the arm 19 and release the stop 13, and by turning the positioning member 29 into different positions, this time interval can be 115 correspondingly varied. The member 29 is 120 herein shown as mounted on the shaft 25 to which the return spring 22 is secured, said shaft being suitably journaled in the clock frame 1. In order to provide for the swinging movement of the carrier 16 I 125 have made said carrier with an enlarged aperture 31 through which the shaft 25 extends, and have formed on said carrier a

hub portion 32 that forms a bearing for the releasing member 14. The shaft 25 will be provided with a suitable thumb-piece by which it may be turned into any adjusted 5 position.

- In order to allow the operator to readily set the positioning member to indicate the desired time interval, I propose, when the device is embodied in an alarm clock, to 10 form the face of the alarm clock 34 with an aperture 33 through which a portion of the positioning member 29 is visible and to graduate the face of the positioning member to indicate the desired time intervals. 15 In the illustrated embodiment of my invention said face is graduated in half hour intervals, and the numbers indicating these half hour intervals are so positioned that by turning the shaft 25 the different figures on 20 the positioning member will be brought into view successively through the sight opening 33. The half hours are indicated by placing the fraction " $\frac{1}{2}$ " directly beneath the figure indicating the hour, said figure being duplicated as shown. Therefore, as the positioning member is turned the numerals "2," 25 "2 $\frac{1}{2}$," "3," "3 $\frac{1}{2}$," etc., will be successively brought into view.

As stated above, the construction is such 30 that the signal may be a short signal or a longer signal. The adjustment of the parts shown in Figs. 1 and 2 is that for giving a short signal which will be sounded while the shaft 8 is making a single revolution. 35 In order to provide for giving a long signal, such as would be given by the running down of the spring 9, I have provided an attachment which can be set to prevent the carrier 16 from returning to its normal position after it has once been lifted by the cam 26 40 thereby holding the stop 13 out of the path of movement of the finger 12. With this arrangement it will be necessary to wind the spring 9 after each alarm. To secure this 45 end I have provided a resilient member 37 secured to the clock frame 1 and which is adapted to engage a shoulder 36 formed on the end of the carrier 16 thereby to prevent the latter from returning to its normal position after it has once been lifted into the 50 position shown in Fig. 2. When the short alarm is to be given the spring 37 is held inoperative by a cam member 38 mounted on a shaft 39 carried by the frame and which is 55 adapted to be turned by any suitable handle, or thumb-piece (not shown) that projects beyond the clock casing. When the shaft 39 is turned into the dotted line position Fig. 2, the member 37 is allowed to move forward into position to engage the shoulder 36. When the carrier 16 is in its lowered or normal position the end of the member 37 rests against the end 40 of the carrier, as shown 60 in Fig. 1. If the cam member 38 is in the

dotted line position Fig. 2, then when the stop 13 is released, as above described, and the cam 26 operates to lift the carrier into the position shown in Fig. 2, the member 37 will move to the right, see Fig. 2, due to its own resiliency and into a position beneath the shoulder 36, so that when the carrier 16 descends after the cam 26 has passed, the shoulder 36 will come into engagement with the end of the member 37, thus holding the carrier elevated to such an extent that the stop 13 will be held out of the path of movement of the finger 12 with the result that the shaft 8 can rotate rapidly until the spring 9 has run down. The shaft 39 carrying the cam 38 is also provided with a locking finger 41 which can be brought against the vibrator 6, as shown in Fig. 6, thereby to lock the alarm mechanism from operation. The shaft 39, therefore, provides not only for controlling the length of time 85 during which the alarm will be sounded but also operates as a means to prevent the alarm from being sounded at all.

In Fig. 5 I have shown a different embodiment of my invention wherein the stop member is rigid with the carrier. This stop member is shown at 130 and when the carrier is in normal position it operates to engage the finger 12 and lock the alarm from operation as above described. In this embodiment the carrier is provided with a projection 131 with which the releasing pin 18 comes in contact. With this construction the engagement of the releasing member 18 with the projection 131 will tend to lock the releasing member from rotation, but the force with which the gear 15 rotates is sufficient to cause the pressure of the releasing member 18 against the projection 131 to force the carrier 16 upwardly to effect the disengagement of the releasing member from the gear 15 and when this occurs the releasing member will be returned to its zero position and the alarm may be sounded, all as above described.

In the above embodiment the invention is shown connected to a driving member 15 that rotates at uniform rate of speed. It will be obvious, of course, that the releasing member will be operated when the driving member 15 has rotated a predetermined number of times, and as the driving member is operating at uniform speed the rotations measure time intervals. If the driving member 15 were rotating at an irregular speed the device would operate just the same, but the alarm would be sounded after a predetermined number of rotations of the driving member 15. The device can, therefore, be used in connection with a driving member 15 whether it is rotating uniformly or at an irregular speed. If it is rotating uniformly

the alarm will sound at regular time intervals, but if it is rotating irregularly, the alarm will be sounded after a predetermined number of rotations of the driving gear and will thus indicate when the driving gear has made said predetermined number of rotations. When used in this way the device would be in the nature of a speed indicator.

I claim:

10 1. In a device of the class described, the combination with a signal mechanism, of means normally locking said mechanism from operation, a driving member, a releasing member driven from the driving member and adapted in its movement to release the locking means for the signal mechanism, means to disengage the releasing member from the driving member when the signal is given, and means to return said releasing member to zero position when it is disengaged.

2. In a device of the class described, the combination with a signal mechanism, of means normally locking said mechanism from operation, a driving member, a releasing member driven from the driving member and adapted in its movement to release the locking means for the signal mechanism, means actuated by the signal mechanism to disengage the releasing member from the driving member when the signal is given, and means to return the releasing member to zero position when it is disengaged.

3. In a device of the class described, the combination with a signal mechanism, of means normally locking said mechanism from operation, a driving member, a releasing member driven from the driving member and adapted in its movement to release the locking means for the signal mechanism, means to disengage the releasing member from the driving member when the signal is given, and a return spring connected to the releasing member to return it to zero position when it is disengaged.

4. In a device of the class described, the combination with a signal mechanism, of means normally locking said mechanism from operation, a driving member, a releasing member driven from the driving member and adapted in its movement to release the locking means for the signal mechanism, means to disengage the releasing member from the driving member when the signal is given, a return spring connected to the releasing member to return it to zero position when it is disengaged, and an adjustable device to limit the return movement of said releasing member.

60 5. In a device of the class described, the combination with a signal mechanism, of means normally locking it from operation, a driving member, a releasing member driven from the driving member and adapt-

ed at a point in its movement to release the locking means for the signal mechanism, means actuated by the signal mechanism to disengage the releasing member from the driving member when the signal is given, a return spring to return the releasing member to zero position when it is disengaged, and an adjustable positioning member to limit the return movement of the releasing member.

6. In a device of the class described, the combination with a signal mechanism, of a stop normally holding said mechanism from operation, a driving member, a releasing member driven from the driving member and arranged at a point in its movement to actuate the stop thereby to release the signal mechanism, means to disengage the releasing member from the driving member when the signal mechanism is operated, and means to restore the releasing member to zero position when the signal is given.

7. In a device of the class described, the combination with a signal mechanism, of a stop device normally holding said signal mechanism from operation, a driving member, a movable carrier, a releasing member carried by said carrier and normally having operative connection with the driving member, said releasing member having means operative in a point in its movement to actuate the stop and release the signal mechanism, means to shift the carrier when the signal is given thereby to disengage the releasing member from the driving member, and means to return the releasing member to zero position when it is thus disengaged.

8. In a device of the class described, the combination with a signal mechanism, of a stop device normally holding said signal mechanism from operation, a driving member, a movable carrier, a releasing member carried by said carrier and normally having operative connection with the driving member, said releasing member having means operative in a point in its movement to actuate the stop and release the signal mechanism, means to shift the carrier when the signal is given thereby to disengage the releasing member from the driving member, means to return the releasing member to zero position when it is thus disengaged, and an adjustable positioning member to limit the return movement of the releasing member.

9. In a device of the class described, the combination with a signal mechanism, of a stop device normally holding said signal mechanism from operation, a driving member, a movable carrier, a releasing member carried by said carrier and normally having operative connection with the driving

member, said releasing member having means operative in a point in its movement to actuate the stop and release the signal mechanism, means actuated by the signal mechanism to shift the carrier when the signal is given thereby to disengage the releasing member from the driving member, and means to return the releasing member to zero position when it is thus disengaged.

10. In a device of the class described, the combination with a signal mechanism, of a stop device normally holding said signal mechanism from operation, a driving member, a movable carrier, a releasing member carried by said carrier and normally having operative connection with the driving member, said releasing member having means operative in a point in its movement to actuate the stop and release the signal mechanism, means actuated by the signal mechanism to shift the carrier when the signal is given thereby to disengage the releasing member from the driving member, means to return the releasing member to zero position when it is thus disengaged, and an adjustable positioning member to limit the return movement of the releasing member.

11. In a device of the class described, the combination with a signal mechanism, of a stop device normally holding said signal mechanism from operation, a driving member, a movable carrier, a releasing member carried by said carrier and normally having operative connection with the driving member, said releasing member having means operative at a point in its movement to actuate the stop and release the signal mechanism, means to shift the carrier when the signal is given thereby to disengage momentarily the releasing member from its driving member, means to return the releasing member to zero position when it is thus disengaged, and means to return the carrier and stop device to normal position after the releasing member has been restored to zero position.

12. In a device of the class described, the combination with a signal mechanism, of a stop device normally holding said signal mechanism from operation, a driving member, a movable carrier, a releasing member carried by said carrier and normally having operative connection with the driving member, said releasing member having means operative in a point in its movement to actuate the stop and release the signal mechanism, means to shift the carrier when the signal is given thereby to disengage momentarily the releasing member from its driving member, means to return the releasing member to zero position when it is thus disengaged, means to return the carrier and stop device to normal position after the re-

leasing member has been restored to zero position, and a device adapted in one position to prevent the carrier from returning to its normal position and in another position to permit said carrier to return to normal position.

13. In a device of the class described, the combination with a signal mechanism, of a spring for actuating the same, means normally locking the signal mechanism from operation, a driving member, a releasing member driven from the driving member and adapted at a point in its movement to release the locking means thereby to permit the signal to be actuated, means to restore the releasing member to its initial position when the signal is sounded, and means to determine the length of time during which the signal will be sounded.

14. In a device of the class described, the combination with a signal mechanism including a shaft, of a finger rigid with said shaft, a stop normally engaging said finger to hold the signal inoperative, a driving member, a releasing member actuated by the driving member and adapted to release the stop from the finger, a cam carried by said shaft and operating to disengage the releasing member from the driving member as the shaft rotates, and means to return the releasing member to zero position when disengaged.

15. In a device of the class described, the combination with a signal mechanism including a shaft, of a finger rigid with said shaft, a stop normally engaging said finger to hold the signal inoperative, a driving member, a releasing member actuated by the driving member and adapted to release the stop from the finger, a cam carried by said shaft and operating to disengage momentarily the releasing member from the driving member, means to return the releasing member to zero position when it is thus disengaged, and means to restore the releasing member to its operative engagement with the driving member.

16. In a device of the class described, the combination with a signal mechanism including a shaft, of a finger rigid with said shaft, a movable carrier, a stop mounted thereon normally engaging said finger thereby to hold the signal mechanism inoperative, a driving member, a releasing member mounted on the carrier and operated by the driving member, and adapted at a point in its movement to release said stop from the finger, a cam carried by the shaft and adapted to engage said stop and thereby shift momentarily the carrier to disengage the releasing member from the driving member, and means to restore the releasing member to zero position when it is disengaged.

17. In a device of the class described, the

combination with a signal mechanism including a shaft, of a finger rigid with said shaft, a movable carrier, a stop mounted thereon normally engaging said finger there-
5 by to hold the signal mechanism inoperative, a driving member, a releasing member mounted on the carrier and operated by the driving member, and adapted at a point in its movement to release said stop from the
10 finger, a cam carried by the shaft and adapted to engage said stop and thereby shift momentarily the carrier to disengage the releasing member from the driving member,

means to restore the releasing member to zero position when it is disengaged, and 15 means to return the carrier to initial position after the releasing member has been returned to zero position.

In testimony whereof, I have signed my name to this specification in the presence of 20 two subscribing witnesses.

SALVATORE MASTROIANNI.
